UNITED STATES PATENT OFFICE.

CONRAD BAUER, OF PITTSBURGH, PENNSYLVANIA.

SCREEN.

1,153,015.

Specification of Letters Patent. Patented Sept. 7, 1915.

Application filed August 22, 1913, Serial No. 786,085. Renewed July 24, 1915. Serial No. 41,798.

To all whom it may concern:

Be it known that I, CONRAD BAUER, a citizen of the United States of America, residing at Pittsburgh, in the county of Allegheny and State of Pennsylvania, have invented new and useful Improvements in Screens, of which the following is a full, clear, and exact description, reference being had to the accompanying drawings, which 10 form part of this specification.

This invention relates to improvements in fly screens and has particular reference to such screens of the rolling type; this invention being especially designed to overcome 15 the difficulties heretofore encountered in the use of wire netting for screens which are not permanently supported in rigid frames. It is a well known fact that the tendency of the stiff material of a wire screen is to kink and 20 wrinkle and become misshaped. That is, it readily bends and normally retains a curved or wavy set as it is unrolled. By my invention I overcome these difficulties by employing means which, while permitting the 25 screen to be wound upon a roller, maintains said screen in a taut condition free from wrinkles or waves.

It consists in the combination and arrangement of parts to be hereinafter more 30 fully described.

Figure 1 is a vertical sectional view of a window provided with my improved screen; showing the roller as mounted within the upper chamber of the window frame or 35 housing; Fig. 2 is an enlarged fragmentary elevational view showing a tension device associated with the lower end of the screen; Fig. 3 is a modified sectional view showing my screen as applied to the outside of an 40 ordinary window frame or similar frame of an opening; Fig. 4 is an enlarged vertical sectional view through the roller of the screen and associated mechanism and showing a cushioned stop or abutment for the 45 roller, to be hereinafter more fully described; Fig. 5 is an enlarged elevational view of the lower portion of the screen and the end weight or slat thereof, showing my 50 invention as applied to screens of great width; a portion of the lower slat being removed to show the clamping means and the

screen being lowered to a position preparatory to stretching and locking in closed position; and Fig. 6 is a similar view showing the screen drawn to a taut condition. 55

In the drawings, 2 represents a roller which may be mounted in any suitable manner at the top of the window frame or casing 3. As shown in Fig. 1 the window casing is provided with an upper chamber 4 which 60 enables suitable mounting of the roller. Where the screen is to be installed in windows or other openings which do not provide or permit of the provision of such an upper chamber 4, said screen may be mounted 65 within the suitable casing 5 at the top of the window. Upon the roller 2 the wire netting or screen 6 is wound, said screen being attached to the roller in any suitable manner. Attached to the lower end of the 70 screen is a slat 7 which is preferably metallic and of such weight as to hold the screen in a taut condition when the said screen is suspended from the roller in the manner shown in Fig. 1. If desired, said weight may take 75 the form of construction disclosed in my Patent No. 1,002,360, dated September 5th, 1911.

As shown in Figs. 1, 3 and 4 the roller 2 is provided with a pivotal dog or stop finger 80 8 which, when the screen is unrolled, drops into a position receivable by a stop or abutment 9 carried by the window frame or any other suitable support. When the screen is rolled up or wound upon the roller 2 the dog 85 8 occupies a position in a recess 11 and flush with the surface of the roller; said dog having a curvature conforming to the circumferential surface of the roller so as to present no obstruction to even and symmetrical 90 rolling of the screen upon the roller.

The roller may be operated in any suitable manner, as by a sprocket or gear 12 (see Fig. 1) carried by the roller and an operating chain 13 associated therewith, as described 95 in my above mentioned Patent No. 1,002,360.

It will be seen that when the screen is lowered to the position shown in Fig. 1, it will unwind from the roller 2 and the dog 8 will drop from the recess 11. Further 100 movement of the roller through action of the weight 7 and lowering of the screen will

bring the dog into abutment with the stop 9 thereby limiting or preventing further movement of the roller, with the result that the weight 7 operates to stretch the suspended screen in such manner as to remove all waviness or wrinkles due to the screen being wound upon the roller.

As shown, the weight 7 may be provided with a suitable clamping means 14 adapted to coöperate with a latch or clip 15 carried by the window frame. It will be seen that when the screen is lowered to the position shown in Fig. 2, the eccentric clamp 14 may be brought into engagement with the clamp 15, through manipulation of the handle 16, so as to draw the screen to a taut condition, the roller being anchored, as above described, and therefore not rotating or yielding under the clamping action of the member 14.

The dogs 8 may be spaced along the roller as desired, and where it is desired to stretch a screen which is of more than the ordinary width, as in large windows or porch screens, I provide a suitable form of clamp which enables a uniform clamping effect along the extended weight or bottom slat, with the manipulation of a single handle or lever. Such an arrangement is shown in Figs. 5 and 6 wherein the lower slat 7 is indicated as having a chamber or recess 17 in which are housed pivotal clamping bars or rods 18 adapted to be brought into terminal engagement with pockets or recesses 19 formed in the upright members 20 or sides of the window frame. The bars 18 are fulcrumed or pivoted as at 21 and connected with the inner ends of the rods 18 is the toggle link arrangement 22 carried by a vertically shiftable or upwardly extending block or finger 23 arranged for coöperative association with which is an eccentric lever or cam member 24 pivoted to the slat 7 and provided with a suitable operating handle 25.

The numeral 26 indicates a coil spring connected to the inner ends of the rods 18 and which tends to normally hold the said rods or bars in a retracted position, as shown in Fig. 5, while a leaf spring 27 tends normally to urge the toggle arrangement and member 23 upwardly as also shown in Fig. 5.

When the screen is lowered to the position shown in Fig. 5 (bearing in mind that the roller is anchored or prevented from rotating after lowering of the screen as above described) by shifting the handle 25 of the cam 24 said cam will bear against and depress the member 23 in such manner as to force and spread apart the toggle links 22 against the tension of the spring 26, thereby bringing the outer ends of the bars 18 into engagement with the pockets 19; the fulcrum 21 of the bars being such as to permit of longitudinal movement of said bars, as by the provision of elongated slots 28. Upon

shifting of the cam member 24 to the position shown in Fig. 6, the member 23 will be so depressed as to bring the lower bearing piece or shoulder 29 thereof into such engagement with the top edges of the bars 18 as to in turn depress or force downwardly the inner ends of the bars causing said bars 18 to swing on the pivotal points or fulcrums 21, with the result that inasmuch as the bars engage the side pockets 19 the lower slats 7 will be forced downwardly to the position shown in Fig. 6, thereby bringing the screen to a taut condition.

As shown in Fig. 4, the abutment 9 may be provided with a yielding stop or spring 80 pressed finger 9' adapted to cushion the ramming movement or engagement of the dog 8 with the abutment. Also such flexibility is advantageous in that it affords a yielding tension to the clamping action described above.

It will be apparent that many changes may be made in the construction shown and described without departing from my invention. While I have shown a particular form of clamping means and device for limiting the movement of the roller it will be apparent, without necessity of specific illustration, that such elements may be changed without departing from their function.

Having thus described my invention, what I claim and desire to secure by Letters Patent is:

1. In a device of the character described, the combination with a frame, of a roller mounted at the top thereof, a screen carried by the roller, a stop carried by the frame, a pivotal dog associated with the roller and adapted to be brought into abutment with the stop, for limiting the rotatory travel of the roller and dependent for operation upon unwinding of the screen from the roller, and means coöperating with said limiting means, for stretching the screen to a taut condition.

2. In a device of the character described, the combination with a frame, of a roller mounted at the top thereof, a screen carried by the roller, means for actuating said roller whereby the screen may be raised and lowered in the frame, a stop carried by the frame, a pivotal dog associated with the roller and adapted to be brought into abutment with the stop, for limiting the rotatory travel of the roller, and means coöperating with the limiting means, for stretching the screen to a taut condition.

3. In a device of the character described, the combination with a frame work, of a screen operatively mounted in said frame work, a bar carried by the lower end of said screen, a plurality of clamping rods associated with said bar, for drawing the screen to a taut condition, and an actuating device commonly associated with said rods.

4. In a device of the character described, the combination with a frame work, of a screen operatively mounted in said frame work, a bar carried by the lower end of said screen, a plurality of clamping members associated with said bar, for drawing the screen to a taut condition; and a cam member mounted intermediate the ends of the bar and adapted to commonly actuate the said clamping members. 10
- 5 In testimony whereof, I have hereunto set my hand in the presence of two witnesses.

CONRAD BAUER.
